United States Patent Office.

FRANCIS HOVEY, OF NEW YORK, N. Y.

Letters Patent No. 98,379, dated December 28, 1869.

IMPROVEMENT IN CARRIAGE-JACKS.

The Schedule referred to in these Letters Patent and making part of the same.

To all whom it may concern:

Be it known that I, FRANCIS HOVEY, of the city, county, and State of New York, have invented a new and useful Improvement in Carriage-Jacks, of which the following is a full, clear, and exact description, reference being had to the accompanying drawing, forming part of this specification, and in which—

Figures 1 and 2 represent side views of a carriage-jack constructed in accordance with my improvement, with the operating parts in different positions.

Figure 3 is a front view of the same.

Similar letters of reference indicate corresponding parts.

My invention consists in a certain combination of lever with a stop or locking projection at its forward end, a toggle-joint motion or motions operated by said lever, and lifting-bar or piece in sliding-roller connection with the stand, the whole constituting a jack that is at once cheap, powerful, and secure.

Referring to the accompanying drawing—

A represents the stand or frame of the jack, formed with back and front sloping guides or bearing-surfaces *a b*, for the stepped lifting-bar or piece B, which is also formed with sloping guides or bearing-surfaces *c d*, to work up and down on or against rollers *e f*, the one of them connected with the lifting-bar B, and the other with the stand A, and operating in connection with the guiding-surfaces *a c*, serving to tie and secure an easy run or travel to the lifting-bar, which, when down, may rest upon top of the stand.

Said lifting-bar is operated by means of a lever, C,

pivoted to the stand, as at S, and made to embrace both sides or surfaces thereof, and with its forward ends or portions formed to constitute stops or locking-surfaces *e e* to (when extended or straightened out) a toggle-joint motion or motions, D, arranged on either side of the stand, and consisting of link-bars *f g*, the one of them pivoted to the stand, and the other to the lifting-bar, and connected, at their pivoted attachment to each other, by link-rods or bars *h*, with the lever C.

A carriage-jack thus constructed may be got up cheap, works easy or free, and is very powerful, also secure as regards its action, without being obliged to have recourse to separate locking-devices, inasmuch as in working the lifting-bar B of the jack from its down position, as shown in fig. 1, to its raised position, as shown in fig. 2, the forward ends or surfaces *e e*, of the lever C, are made to act as stops to the straightened toggle-joints D, to lock or hold the same and the lifting-bar B, carried by them.

What is here claimed, and desired to be secured by Letters Patent, is—

The combination of the lever C, with its locking-surfaces or stops *e*, the toggle-joint motion or motions D, and the lifting-bar B, in roller-sliding connection with the stand A, substantially as shown and described.

FRANCIS HOVEY.
